UNITED STATES PATENT OFFICE.

CHARLES E. DATH, OF CHICAGO, ILLINOIS, ASSIGNOR TO WILLIAM H. MINER, OF CHAZY, NEW YORK.

YOKE.

1,286,245.

Specification of Letters Patent.

Patented Dec. 3, 1918.

Application filed August 20, 1917. Serial No. 187,202.

To all whom it may concern:

Be it known that I, CHARLES E. DATH, a citizen of the United States, residing at Chicago, in the county of Cook and State of Illinois, have invented a certain new and useful Improvement in Yokes, of which the following is a full, clear, concise, and exact description, reference being had to the accompanying drawings, forming a part of this specification.

This invention relates to improvements in yokes.

One object of the invention is to provide a relatively inexpensive and efficient yoke for railway draft riggings.

Another and more specific object of the invention is to provide a yoke which is adapted for detachable connection with a standard draw bar and is so designed as to permit the reemployment of old yoke straps of the riveted type with consequent saving to the users.

In the drawing forming part of this specification, Figure 1 is a part vertical section, 25 part side elevation of a draw bar and yoke showing my improvements in connection therewith. Fig. 2 is a top plan view of the front portion of the yoke and rear end of the draw bar illustrated in Fig. 1. Fig. 3 is a vertical, transverse, sectional view, taken 30 on the line 3—3 of Fig. 1. And Fig. 4 is a view corresponding to Fig. 1, but illustrating another embodiment of the invention.

Referring to the construction illustrated 35 in Figs. 1, 2 and 3, 10 denotes the shank of a standard draw bar having the usual butt 11 and coupler key slot 12. The yoke, as shown, comprises, broadly, a hollow rectangular hood or head A and a yoke strap B. The head A is provided with slightly flaring vertical side walls 13—13, vertically arranged upper and lower transversely extending cross bars or walls 14—14 and horizontal connecting and draw bar guiding walls 15—15. The walls 15—15 are spaced vertically a distance corresponding to the vertical height of the draw bar butt so as to properly guide and support the latter. 45 The inner faces of the cross bars 14—14 are spaced apart vertically a distance equal substantially to the vertical height of the draw bar but plus twice the thickness of the strap forming the loop B.

It will also be noted that the cross bars 14 55 are located at the rear of the head A for the purpose hereinafter described. The head A and draw bar are detachably connected by a coupler key 16 which extends through the slot 12 and corresponding slots 60 provided in the side walls 13 of the head.

The yoke strap or loop B is of well known form and preferably made of wrought iron. Said member B comprises upper and lower arms 17—17 connected at their rear ends 65 by a vertical section 18, the latter preferably having secured to its inner face a filler block 19. At their front ends, the arms 17—17 have upwardly and downwardly bent flange portions 20—20 which are provided with 70 rivet holes 21—21 in alinement with corresponding rivet holes 22—22 in the cross bars 14.

The arrangement is such that the yoke member B may be an old yoke of the so-called riveted type and in actual practice, the location of the cross bars 14 of the head will be such that, when the forward ends of the old yoke strap are bent upwardly and downwardly, as indicated, the rivet holes 75 21 therein which originally corresponded to the rear rivet holes 23—23 of the draw bar, will align with said rivet holes 22—22 of the cross bars 14. When thus bent, the strap is connected to the hood by rivets 80 24—24 and any metal on the ends of the strap after the latter has been flanged upwardly and downwardly, as above indicated, can be cut off flush with the outer faces of 85 the cross bars 14.

With the arrangement above described, it is obvious that I have provided an exceedingly inexpensive yoke for railway use inasmuch as the amount of metal required in the cast head A is reduced substantially 90 to a minimum and the railroads can reemploy the old yoke straps of the riveted type, thus saving the expense of the strap. Not only this, but the arrangement is such that a very strong connection is provided between 95 the strap and the head since the upwardly and downwardly bent portions 21 of the strap are placed in direct shear across their entire width and the rivets 24—24 are subject to very little stress either tension or 100 shear.

With my arrangement, the connection between the strap and head is such that break-

age will not occur at the connection inasmuch as this affords a maximum resistance since the entire strap is under shear.

At the same time, it is also apparent that 5 I have provided a detachable connection for the draw bar with the consequent advantages as compared with the old type of riveted yoke strap.

In the construction illustrated in Fig. 4, 10 the connection between the head A' and yoke strap B' is substantially identical with that disclosed in the other three figures except that the lower cross bar 114 of the head is extended somewhat to the rear of 15 the upper cross bar 114. This is done in order to permit the draw bar butt 111 to drop downwardly when it is disconnected from the head, as hereinafter described. In 20 this construction, the arrangement permits 20 of a detachable connection with any standard draw bar whether the same has a coupler key slot or not, and in order to carry out this function, the head A' is provided across 25 the upper portion thereof with an integral wall 115 having a downturned gib 40 at its front edge which is arranged to engage the upper shoulder 41 of the draw bar butt. At 30 its lower end, the head A' is provided with a lower horizontal integral wall 42 which is spaced sufficiently below the gib 40 as to permit the insertion of the draw bar butt longitudinally beneath the gib. After the 35 draw bar butt has been inserted, as above described, it is held in elevated position and in coöperative engagement with the gib 40 by means of a transversely extending locking and supporting block 43, the latter also having an upturned gib 44 at its front edge arranged to engage the lower shoulder 45 40 of the draw bar butt. Said block 43 is inserted laterally through the side walls of

the head A', said walls being provided with slots corresponding in size and shape to said block 43. The latter can be held against accidental lateral movement by any suitable means, such as cotter 46. The arrangement 45 illustrated in Fig. 4 obviously has all of the advantages above described in connection with the structure illustrated in the other three figures.

I claim:

1. A yoke of the character described comprising, a hollow head adapted to be detachably connected to a draw bar, and a yoke strap, said head having upper and lower transversely extending cross bars at the rear thereof, said yoke strap having the front ends of the arms thereof bent outwardly against the forward faces of said cross bars and riveted thereto.

2. As an articles of manufacture, a yoke 60 for railway draft riggings, said yoke comprising a hollow head adapted to be detachably connected to a draw bar, said head having vertical side walls and upper and lower transversely extending cross bars at the rear end thereof; a U-shaped strap having the forward ends thereof bent upwardly and downwardly, respectively to overlie the front faces of said cross bars, said cross bars 65 and the bent ends of said yoke being provided with aligned openings; and securing means extending through said openings, the location of the openings in the bent portions of the yoke strap corresponding to the position of the rear rivet holes of a U-shaped 70 yoke strap of the riveted type.

In witness that I claim the foregoing I have hereunto subscribed my name this 29 day of July, 1917.

CHARLES E. DATH.
